UNITED STATES PATENT OFFICE

157,428

BEVERAGE BREWER

Harper Richards, Chicago, Ill., assignor to Cory Corporation, Chicago, Ill., a corporation of Delaware

Application December 2, 1948, Serial No. 149,928

Term of patent 14 years

(Cl. D44—26)

To all whom it may concern:

Be it known that I, Harper Richards, a citizen of the United States, residing at Chicago, in the county of Cook and State of Illinois, have invented a new, original, and ornamental Design for a Beverage Brewer, of which the following is a specification, reference being had to the accompanying drawing, forming part thereof, where-in—

Fig. 2 is a top plan view thereof.

I claim:

The ornamental design for a beverage brewer, as shown.

HARPER RICHARDS.
